CLAIM

The ornamental design for a display screen with graphical user interface for a laboratory instrument, as shown and described.

DESCRIPTION

FIG. 1 is a front view of a first embodiment of the display screen with graphical user interface for a laboratory instrument; and

FIG. 2 is a front view of a second embodiment thereof. The interior broken lines in the Figures illustrate portions of the graphical user interface that form no part of the claimed design. The broken line perimeter in the Figures is included for the purpose of showing a display screen and forms no part of the claimed design.
